UNITED STATES PATENT OFFICE.

JOHN BEAULIEU, OF MALDEN, MASSACHUSETTS.

COIN BANK.

Application filed June 20, 1921. Serial No. 479,077.

To all whom it may concern:

Be it known that I, JOHN BEAULIEU, a citizen of the United States, residing at Malden, in the county of Middlesex and State 5 of Massachusetts, have invented new and useful Improvements in Coin Banks, of which the following is a specification.

This invention relates to banking machines and has for its object the provision of 10 a machine containing receipt checks and so constructed as to eject a check when a coin is deposited within a slot provided for the purpose, it being readily apparent that the device may be constructed of any desired 15 number of units whereby to take care of any or all denominations of coins, it being therefore quite readily apparent that the device is capable of extensive use in a banking system on a small scale, each unit of course showing 20 a characteristic check or receipt corresponding to the coin deposited.

An important object is the provision of a device of this character having novel ejecting means which is operable automatically 25 when a coin is pressed into the proper receiving slot.

An additional object is the provision of a device of this character which will be simple and inexpensive in manufacture, easy to operate, not likely to get out of order, durable in service, and a general improvement in the 30 art.

With the above and other objects and advantages in view, the invention consists 35 in the details of construction to be herein-after more fully described and claimed and illustrated in the accompanying drawings in which—

Figure 1 is a front elevation of the complete device showing it adapted for handling 40 coins of several different denominations.

Figure 2 is a front elevation of one unit and parts of adjacent units, parts being broken away and in section,

Figure 3 is a vertical section on the line 45 3—3 of Figure 2.

Figure 4 is a horizontal section on the line 4—4 of Figure 2,

Figure 5 is a vertical section on the line 50 5—5 of Figure 2,

Figure 6 is a bottom plan view of the receipt check container, and

Figure 7 is a bottom plan view of the coin receiver.

Referring more particularly to the drawings, I have shown my device as comprising

a rectangular casing 10 provided of course with a door 11 which is capable of being opened for the purpose of permitting access to the interior of the casing, this door being 60 provided with any suitable locking device, not shown. Located within this casing are horizontal partitions 12 which divide the interior into different compartments, the number of compartments desired depending 65 upon the denominations of coins intended to be handled by the bank.

Each compartment is designed to contain a plurality of receipt checks and is also designed to receive coins. In carrying out 70 this construction I provide a cylindrical container 13 which is initially filled with receipt checks indicated by the letter A. This container is open at one side, for a purpose to be described, and is held in place by being 75 provided at one end with flanges 14 engaging within the retaining strips 15 secured upon the underside of the partition 12 immediately above. The cover 11 is provided preferably, though not necessarily, opposite each 80 container 13 with a glass panel 16 which permits inspection so that a prospective patron of the machine may ascertain whether or not a certain compartment contains receipt checks of a given denomination or 85 whether it is empty. A portion of each container 13 is cut away, as shown at 17, opposite the panel 16. At its lower end the container 13 rests upon a partition 12 but is cut away, as shown at 17^a, for a purpose to 90 be described, this cut away portion being in alignment with a slot 18 in the front of the casing.

Associated with each container 13 but located below and to one side thereof, is a 95 coin deposit receptacle 19 which is cylindrical and which may have one side cut away, as shown at 20, so that the prospective patron, or the operator of the machine, may glance through a glass panel 21 and ascertain 100 whether or not any coin receptacle is full. Each coin receptacle is preferably provided with a flaring upper end, indicated at 22, this upper end being located beneath a hole 23 located in the partition above. The flaring 105 end is formed with flanges 22^a slidably engaging retaining strips 22^b on the partition. The casing is provided with a slot 24 immediately above the partition beneath which the coin receptacle is located, this slot permitting the insertion of a coin.

Associated with each receipt check con-

tainer and coin receptacle is an obtuse angular lever 25 pivoted, as at 26, upon the associated partition 12 and one arm 27 of this lever is located to the rear of the lower 5 end of the receipt check container in position to engage the lowermost receipt check in the latter. The other arm 28 of this lever carries a crescent shaped coin grip 29 which normally extends across the opening 23, this 10 crescent shaped member being of course opposite a slot 24. The lever 25 is normally held in this position by a coil spring 30 which is connected with the arm 27 and which holds the arm 27 against a stop 31. 15 It is preferable, though not essential, to provide a slide 32 associated with each slot 24, this slide having an upturned outer flange 33 and having a semi-circular countersunk portion 34 whereby to hold a coin 20 initially.

The operation of the device is as follows: Assuming that the receipt check containers 12, regardless of how many there may be, are full, as they should be at starting, a patron desiring to make a deposit selects the proper slot 24, depending upon the denomination of the coin he wishes to deposit. He then pulls out the slide 32 in the selected slot 24, places the coin in the slide, the coin 25 engaging upon the countersunk portion 34, and then presses the slide inwardly. The coin will shortly engage against the crescent shaped coin grip 28 and as the slide is still further pressed the lever 25 will be rocked 30 upon its pivot 26 whereupon the lever arm 27 will engage the rear edge of the lowermost receipt check and eject the same through the slot 18, the patron taking this receipt check as evidence of his deposit. At 35 the time when the lever 25 has been fully operated, the concave edge of the grip member 29 will register with the hole 23 whereupon the coin will drop from the slide 32, through the opening 23 and through the flared upper end into the body of the coin receptacle 19. When the coin drops the spring 30 will return the parts to their 40 initial position ready for subsequent operation. 45 From the foregoing description and a study of the drawings it will be apparent that I have thus provided a simply constructed and consequently inexpensive machine enabling banking to be conducted on a small scale, it being conceivable that the device might be used in stores of any kind or other locations found convenient or suitable. Owing to the extreme simplicity of the construction it will be apparent that 50 there will be nothing to get out of order and that the device should consequently have a long life. A distinct advantage is the fact that no operator is necessary other than a duly authorized attendant to inspect the machine periodically, remove the coins there- 55

from and replenish the stock of receipt checks.

While I have shown and described the preferred embodiment of my invention, it is of course to be understood that I reserve 70 the right to make such changes in the form, construction and arrangement of parts as will not depart from the spirit of the invention or the scope of the subjoined claims.

Having thus described my invention, I 75 claim:

1. A device of the character described comprising a casing provided in its front with spaced slots arranged in horizontal alignment, a partition within the casing 80 formed with a hole, a coin receptacle supported from the partition and located beneath the hole, a receipt check container having its lower end spaced above the partition, and lever means mounted on the partition and engageable by a coin pressed into one slot whereby to eject the lowermost receipt check through the other slot. 85

2. A device of the character described comprising a casing provided with spaced 90 horizontally aligned slots, a partition within the casing formed with a hole, a coin receptacle located beneath said hole, an upstanding receipt check container spaced above the partition, said coin receptacle being opposite one slot and the check container being opposite the other, and means operated by insertion of a coin through one slot for ejecting a receipt check through the other slot. 95

3. A device of the character described comprising a casing provided with spaced horizontally aligned slots, a partition within the casing formed with a hole, a coin receptacle located beneath said hole, an upstanding receipt check container spaced above the partition, said coin receptacle being opposite one slot and the check container being opposite the other, and means operated by insertion of a coin through one 100 slot for ejecting a receipt check through the other slot, said means comprising an angular lever pivoted upon the partition and having one arm disposed rearwardly of the lowermost check in the stack and having its 105 other arm provided with a crescent shaped coin grip. 110

4. A device of the character described comprising a casing provided with spaced horizontally aligned slots, a partition within 120 the casing formed with a hole, a coin receptacle located beneath said hole, an upstanding receipt check container spaced above the partition, said coin receptacle being opposite one slot and the check container being 125 opposite the other, and means operated by insertion of a coin through one slot for ejecting a receipt check through the other slot, said means comprising an angular lever pivoted upon the partition and having one arm 130

disposed rearwardly of the lowermost check in the stack and having its other arm provided with a crescent shaped coin grip, said coin receptacle having a flaring upper end 5 facilitating passage of coins thereinto, and a slide operating within the coin receiving slot and cooperating with said coin grip, a coin serving as the connecting medium.

5. A device of the character described 10 comprising a casing provided with spaced horizontally aligned slots, a partition within the casing formed with a hole, a coin receptacle located beneath said hole, an upstanding receipt check container spaced above the 15 partition, said coin receptacle being oppo-

site one slot and the check container being opposite the other, and means operated by insertion of a coin through one slot for ejecting a receipt check through the other slot, said means comprising an angular lever pivoted upon the partition and having one arm disposed rearwardly of the lowermost check in the stack and having its other arm provided with a crescent shaped coin grip, said coin receptacle and said check container 20 being slidably removably supported with respect to the partition.

In testimony whereof I hereto affix my signature.

JOHN BEAULIEU.
